Atty's.

UNITED STATES PATENT OFFICE.

ALBERT D. GROVER, OF NEW YORK, N. Y.

TUNING-PEG FOR STRINGED MUSICAL INSTRUMENTS.

1,384,459.

Specification of Letters Patent. Patented July 12, 1921.

Application filed August 11, 1919. Serial No. 316,614.

To all whom it may concern:

Be it known that I, ALBERT D. GROVER, a citizen of the United States, and a resident of New York city, in the county of New York and State of New York, have invented certain new and useful Improvements in Tuning-Pegs for Stringed Musical Instruments, of which the following is a specification.

10 My invention relates in general to stringed musical instruments and its object is to provide a new tuning peg, which by reason of certain novel features effectively overcomes the objections inherent in pegs of prior construction.

As those skilled in the art well know, the tuning pegs heretofore used on banjos and like instruments, have been clamped to the peg-head by a retaining screw passing through the thumb-piece. This clamping was effected by means of a pair of shoulders or collars engaging the opposite faces of the peg-head. This frictional engagement was not yieldable but rigid. As a result, when the peg was turned in tuning the attached string, the retaining screw would frequently become loose and the peg would consequently slip. This has always been a source of great annoyance to the players, and required frequent adjustment of the retaining screw. If the peg was too tight it would not turn with the required ease; if too loose it slipped.

The foregoing objections are entirely overcome by the tuning peg of my invention. Broadly speaking, one feature of my invention resides in the provision of elastic friction means for securely holding the peg in any adjusted position. This basic idea may be mechanically carried out in different ways. In the preferred embodiment of my invention, as now best known to me, this friction means is in the form of a coil-spring mounted on the shank of the peg to force the head-engaging parts of the peg into frictional contact with the opposite faces of the peg-head. The result is, that the peg is held in adjusted position with the right degree of friction, being neither too tight nor too loose, and it is impossible for it to become loose when turned, as in tuning.

The tuning peg of my invention is also

provided with means for quickly and easily attaching the string to the peg. In the tuning pegs heretofore in use on banjos, violins and other stringed instruments, the only way 55 that the players could attach the string, was by inserting it through the small hole in the shank of the peg and then turning the peg several times to overlap the inserted end of the string. For this purpose it was necessary that the string should be long enough to extend some distance through the opening, otherwise the string could not be wound on itself sufficiently to prevent unwinding when the string was tuned up to the proper pitch. 60 Furthermore, if the string broke at the tail-piece, where it usually does, there was not enough length of string left to fasten to the peg by the overlapping method as just referred to, and the string had to be thrown 65 away. This has been a source of expense to the player, increasing with the increasing cost of strings.

The foregoing defect is done away with entirely by the use of the string attaching 75 device with which my peg is provided. By means of this device the string is firmly clamped in the hole of the peg without any overlapping of string. No extra length of string is needed, but it may be attached to 80 the peg if it is just long enough to insert into the hole. Furthermore, the string can be attached instantly. In the preferred form of my invention, this clamping device for the string is a set-screw which is readily 85 worked by the fingers. The inner end of the screw bears against the end of the string in the hole and firmly clamps the same against slipping.

The foregoing and other objects and advantages of my invention will become apparent from a detailed description of the several forms shown in the accompanying drawings in which—

Figure 1 is a longitudinal section of a preferred form of tuning peg embodying my invention, certain parts being shown in full for the sake of clearness;

Fig. 2 is a transverse cross-section on line 2—2 of Fig. 1, looking in the direction of the 100 arrows;

Fig. 3 is a view similar to Fig. 1, showing

a somewhat modified construction in which the two sleeves for the coil-spring are omitted;

Fig. 4 is a transverse section on line 4—4 of Fig. 3, looking in the direction of the arrows;

Fig. 5 is a longitudinal view, mainly in cross-section, of another modified construction in which a ring of rubber or similar elastic material is used in place of the spring;

Fig. 6 is a transverse cross-section on line 6—6 of Fig. 5, looking in the direction of the arrows;

Fig. 7 is a view partly in cross-section of still another modification using a rubber ring for the elastic friction means;

Fig. 8 shows a still further modified form partly in cross-section employing a coil-spring, and

Fig. 9 shows a violin peg provided with my new string attaching device.

Referring to the form shown in Figs. 1 and 2, the peg has a shank 1 which passes through the usual opening 2 in the peg-head 3 of the instrument. I have shown the peg-head 3 merely in a conventional way, but that is sufficient for those skilled in the art. The shank 1 has a shoulder or enlargement 4, which is of greater diameter than the peg-hole 2, and is adapted to be drawn into frictional engagement with the face 5 of the peg-head. Beyond the friction shoulder 4, the peg is formed with an extension 6 having the usual hole 7 for receiving the end of the string 8. The extension 6 is provided with an axial bore or opening 9 for receiving the set-screw 10. This set-screw is preferably provided with a knurled or roughened head 11, slightly larger than the end flange 12 of the extension 6, so that the head 11 may be easily grasped by the fingers and turned. It will be clear from Fig. 1 that to fasten the string 8 to the peg, it is only necessary to insert the end of the string into the hole 7 far enough to reach the set-screw 10 and then give the set-screw a few turns to clamp the string firmly in the opening 7. This is but the work of a moment, and overcomes all the difficulties and disadvantages of attaching the string to the pegs of prior construction, as previously explained.

Still referring to Fig. 1, the shank 1 of the peg has mounted thereon a sleeve 13 which is open at its outer end 14, but is at its inner end provided with a shoulder 15 adapted to come into frictional contact with the face 16 of the peg-head 3. A second sleeve 17 is also mounted on the shank 1 of the peg in such a way that the sleeves 13 and 17 form a chamber or housing for the coil-spring 18. One end of this spring bears against the shoulder 15 of the sleeve 13, and the other end against the flange 19 of the

sleeve 17. The tendency of the spring 18 is to force the sleeves 13 and 17 apart.

The peg is provided with a thumb-piece 20 of usual construction, having an angular opening 21, into which fits the angular section 22 of the shank 1. The thumb-piece 20 has an opening 23 in alignment with the screw-threaded axial opening 24 of the shank. A retaining screw 25 passes through the opening 23 into the screw-threaded opening 24, whereby the thumb-piece 20 is rigidly secured upon the shank 1. It will be clear that by turning the screw 25, the position of the thumb-piece 20 and therefore the position of the sleeve 17, is adjustable on the shank 1. In this way the tension of the spring 18 may be regulated. By adjusting the thumb-piece away from the peg-head 3, the slidble sleeve 17 at once follows it and the spring 18 expands, thereby reducing its tension. To increase the tension of the spring 18, the thumb-piece 20 is moved toward the peg-head 3 by means of the screw 25.

It will be clear from Fig. 1, that the tendency of the spring 18 is to urge the annular shoulders 4 and 15 into frictional engagement with the opposite faces of the peg-head 3, whereby the peg is securely held against slipping in any position to which it may be adjusted in tuning. The degree of pressure with which the shoulders 4 and 15 bear against the faces of the peg-head, is readily regulated by the player by a slight turning of the screw 25, as already explained. It will be observed that the frictional engagement of the shoulders 4 and 15, with the opposite faces of the peg-head, is not rigid as in the pegs of prior construction, but is yieldable and automatically adjustable. Even if the screw 25 should slightly turn while the player is manipulating the peg to tune the string, this turning of the screw will not entirely loosen the frictional contact between the peg and the head.

In Fig. 3 is shown a slightly modified form of construction. The coil-spring 18^a bears at its inner end against the washer 26 and at its other end against the shoulder 27 of the thumb-piece 20. The washer 26 has an angular opening through which passes the angular section 22 of the shank. There is also a washer 28 interposed between the shoulder 4^a of the peg and the adjacent face of the peg-head 3. The operation of the spring 18^a is precisely the same as the spring 18 in the construction of Fig. 1. The spring 18^a being under tension forces the shoulder 4^a into frictional engagement with the interposed washer 28 and the latter is drawn into frictional engagement with the face of the peg-head. At the same time the washer 26, which constitutes in effect a shoulder like the shoulder 15 of Fig. 1, is forced by the spring

18^a into frictional contact with the adjacent face of the peg-head. The result is the same as that described in connection with Fig. 1. The tension of the spring 18^a may be regulated by means of the screw 25, in the same manner as described in connection with the spring 18 of Fig. 1.

In the form shown in Fig. 5, I use a ring 29 of rubber or other elastic material. 10 The elastic ring 29 is interposed between the washers 30 and 31. The washer 31 bears against the thumb-piece 20^a and may be provided with an annular flange 32 fitting into a corresponding recess into the thumb-piece 15 20^a. The parts 30, 29, 31 and 20^a are all provided with angular openings to receive the angular section 22^a of the peg, so that when the peg is turned, all of these parts turn together. By adjusting the screw 25^a 20 which passes through the thumb-piece into the screw-threaded opening 24^a of the peg, the tension of the elastic ring 29 may be adjusted. When the elastic ring 29 is placed under compression by forcing the thumb-piece 20^a and washer 31 toward the peg-head by means of the retaining screw 25^a, the action of the elastic ring is to force the washers 30 and 28^a into frictional contact with the opposing faces of the peg-head. 30 Of course, the head or shoulder 4^b of the peg will be forced against the interposed washer 28^a. Should any loosening of the screw 25^a occur, the elastic ring 29 will immediately expand and maintain the head-engaging parts of the peg in firm frictional contact with the peg-head.

In Fig. 7 I have shown another way of mechanically carrying out the basic idea of my invention. This form is in a way a combination of certain features shown in Figs. 1 and 5. An elastic ring 29^a is housed in the recess or chamber formed by the sleeve 13^a and the tension screw 33, which is threaded on the threaded portion 34 of the peg shank 1^a. The tension screw 33 has a knurled or roughened finger portion 35, by means of which the screw is adjustable axially on the peg-shank. The sleeve 13^a is similar to the sleeve 13 of Fig. 1 and is provided with a shoulder 15^a which engages the adjacent face of the peg-head 3. The shank 1^a is provided with an annular head or shoulder 4^b which is similar to the shoulder 4 of Fig. 1 and is arranged to bear against the adjacent face of the peg-head. It will be clear, that when the tension-screw 33 is screwed toward the peg-head, the elastic ring 29^a is put under tension and it acts to force the shoulders 4^b and 15^a into frictional engagement with the opposing faces of the peg-head, thereby holding the peg firmly in adjusted position. The thumb-piece 20^b of Fig. 7 is secured to the peg-shank by the screw 25^b in exactly the

same way as the thumb-pieces of the constructions previously described.

In the modification of Fig. 7, the thumb-piece 20^b performs the additional function of acting as a check-nut for the tension-screw 33. In other words, when the tension-screw 33 has been adjusted into the desired position, the thumb-piece 20^b is so adjusted as to bear firmly against the flange 36 of the screw 33, whereby the latter is held against accidental turning.

The form shown in Fig. 8 is practically the same as the one shown in Fig. 7, except that in place of the elastic ring 29^a I use a coil-spring 18^b. The sleeve or cup-shaped washer 37 and the slideable sleeve 38 form a housing or recess 39 in which the spring 18^b is retained. The two cup-shaped sleeves 37 and 38 are provided with angular openings through which passes the correspondingly shaped section 22^b of the peg-shank, so that those two parts turn with the peg. The sleeve 38 is provided with a knurled or roughened finger portion 40, by means of which the sleeve is radially turned. The sleeve 38 is also provided with a screw-threaded section 41, which engages the screw-threaded extension 42 of the thumb-piece 43. As in the case of the other thumb-pieces, the thumb-piece 43 is secured to the shank of the peg by the screw 44 which engages the screw-threaded opening 45 of the peg-shank. To adjust the position of the sleeve 38 on the shank, it is only necessary to loosen the screw 44, which permits the turning of the tension-sleeve 38 into the position to adjust the tension of the spring 18^b to the desired degree. After the sleeve 38 has thus been adjusted, the screw 44 is turned home and the parts 38 and 43 are held rigidly as a single member on the shank of the peg.

The action of the spring 18^b is precisely the same as the action of the springs and elastic rings previously referred to; that is to say, the spring 18^b will force the cup-shaped washer 37 and the shoulder or enlargement 4^c into frictional contact with the opposite faces of the peg-head 3, whereby the peg is firmly held against slipping. Any accidental loosening of the screw 44 is at once taken up by the spring 18^b, so as to maintain the frictional engagement with the peg and the head.

The foregoing modifications have been described for illustrative purposes only, and not by way of limitation. The basic idea of a tuning peg having elastic friction means which automatically maintain the frictional engagement between the peg and the head, may undoubtedly be mechanically embodied in other forms than the illustrations herein presented.

In Fig. 9 I have shown a section of the peg-box or peg-head of a violin. The tuning

peg shown in this figure is not provided with the elastic friction means shown in the other figures, but is provided with the string attaching device previously described in connection with Fig. 1. The peg 46 is provided with the usual string receiving opening 47. At the adjacent end the peg 46 is provided with the axial bore or opening 48, which is screw-threaded to receive the set-screw 49.

10 I prefer to provide the set-screw 49 with a knurled head 50, which is slightly larger in diameter than the end of the peg so that it can be easily grasped by the fingers and the screw adjusted into the desired position.

15 The axial bore 48 meets the radial opening 47, so that when the clamping screw 49 is screwed home, the string A will be clamped firmly in the opening 47. My string-clamping device is especially useful on violin pegs, because it is a well known fact, that owing to the construction of the peg-box on violins, it is a difficult and tedious job to attach a string by the old method of overlapping, as explained in detail in connection 20 with Fig. 1. By the use of my string-clamping device, the player merely has to insert the end of his string into the string opening and then tighten the clamping-screw 49. This is but the work of a moment. Furthermore, as was explained in connection with 25 the banjo peg of Fig. 1, my new string attaching device permits the attachment of a string which would be too short for pegs of the old construction. If the violin player has a string just long enough to go into the opening 47 far enough to reach the screw 49, he can attach his string without any difficulty.

It is obvious that the two main features 40 of my invention, namely, the elastic friction means and the string-clamping device need not be used together in the same peg. For instance, in the violin peg of Fig. 9, the elastic friction means is not necessary, but 45 in the case of a banjo I should say it would be advisable to use a peg embodying both features.

Having thus described my invention what 50 I claim as new and desire to secure by Letters Patent of the United States is:

1. A tuning peg for stringed musical instruments, comprising an integral shank having a cylindrical portion to enter a peg hole and a polygonal portion provided at 55 one end with a thumb-piece, a pair of relatively slidably shoulders on said shank to engage the opposite faces of the peg-head, and elastic means for forcing said shoulders toward each other into frictional engagement with the opposite faces of the peg-head.

2. A tuning peg for stringed musical instruments, comprising an integral shank having a cylindrical portion to enter a peg 60 hole and a polygonal portion provided at

one end with a thumb-piece, a pair of relatively slidably shoulders on said shank to engage the opposite faces of the peg-head, and elastic means for forcing said shoulders toward each other into frictional engagement with the opposite faces of the peg-head, and means for adjusting the tension of said elastic means. 70

3. A tuning peg for stringed musical instruments, comprising an integral shank having a cylindrical portion to enter a peg hole and a polygonal portion provided at one end with a thumb-piece, a pair of relatively slidably shoulders on said shank to engage the opposite faces of the peg-head, and elastic means for forcing said shoulders toward each other into frictional engagement with the opposite faces of the peg-head, said thumb-piece being adjustable along the axis of said shank to vary the tension of said 80 elastic means.

4. A tuning peg for stringed musical instruments, comprising an integral shank having a cylindrical portion to enter a peg hole and a polygonal portion provided at 90 one end with a thumb-piece, friction means on said shank for engaging the peg-head, and elastic means on said shank adapted to act upon said friction means and thereby maintain said frictional engagement practically constant, whereby the peg is securely held in adjusted position in the peg-head. 95

5. A tuning peg for stringed musical instruments, comprising an integral shank having a cylindrical portion to enter a peg 100 hole and a polygonal portion provided at one end with a thumb-piece, a pair of relatively slidably shoulders on said shank to engage the opposite faces of the peg-head, and a coil-spring on said shank for forcing 105 said shoulders toward each other into frictional engagement with the opposite faces of the peg-head.

6. A tuning peg for stringed musical instruments, comprising an integral shank 110 having a cylindrical portion to enter a peg hole and a polygonal portion provided at one end with a thumb-piece, a shoulder on said shank near the other end thereof and adapted to engage one face of the peg-head, 115 a pair of sleeves slidably mounted on said shank and forming a chamber or housing, one of said sleeves having means at one end for frictionally engaging the adjacent face of the peg-head, the other sleeve being arranged to bear at its outer end against said thumb-piece, and an elastic member in said chamber for forcing said shoulder and said first mentioned sleeve into engagement with the opposite faces of the peg-head. 120

7. A tuning peg for stringed musical instruments, comprising an integral shank having a cylindrical portion to enter a peg hole and a polygonal portion provided at one end with a thumb-piece, a shoulder on 125

said shank near the other end thereof and adapted to engage one face of the peg-head, a pair of sleeves slidably mounted on said shank and forming a chamber or housing, one of said sleeves having means at one end for frictionally engaging the adjacent face of the peg-head, the other sleeve being arranged to bear at its outer end against said thumb-piece, an elastic member in said

chamber for forcing said shoulder and said 10 first mentioned sleeve into engagement with the opposite faces of the peg-head, and means for adjusting the tension of said elastic member.

In witness whereof, I hereunto subscribe 15 my name this 8th day of August, 1919.

ALBERT D. GROVER.
